UNITED STATES PATENT OFFICE.

EDWIN LUNDGREN, OF FREDERICK, MARYLAND, ASSIGNOR TO INTERNATIONAL COMBUSTION ENGINEERING CORPORATION, OF NEW YORK, N. Y., A CORPORATION OF DELAWARE.

UNDERFEED STOKER.

Application filed February 23, 1924. Serial No. 694,484.

My invention relates to underfeed stokers, and has special reference to underfeed stokers of the type having a plurality of downwardly and rearwardly inclined retorts having longitudinally movable side walls and tuyère structures mounted upon the side walls.

In stokers of this type, as heretofore constructed, the feeding of the fuel through the retorts and into the furnace depends entirely upon the feeding action of the primary ram at the forward end of each retort, and the action of the tuyère structures carried by the side walls to drag the fuel out from the retorts and distribute it over the tuyère structures. This action is not very positive and becomes aggravated as the length of the stoker is increased.

Another disadvantage of stokers of this type as heretofore provided, is that with the use of coking fuels, the fuel cokes in a mass in the retort during banking hours and there is no means to break up this coke formation when the stoker is again started without resorting to bars or other make-shifts to do so.

The object of the present invention is to overcome the disadvantages above referred to of underfeed stokers of the type indicated, as will hereinafter appear.

The following is a description of my invention reference being had to the accompanying drawings, in which,

Figure 1 is a longitudinal sectional view of an underfeed stoker embodying the features of the invention in their preferred form;

Fig. 2 is a transverse sectional view on an enlarged scale taken on the line 2—2 of Fig. 1; and

Fig. 3 is a detail sectional view corresponding to a portion of Fig. 2 but showing a slightly modified construction.

The underfeed stoker illustrated in the drawings is of the type of the one illustrated and described in the Patent to Riley, No. 1,322,822, dated Nov. 25, 1919. As shown this stoker comprises an underfeed grate 2, and an overfeed grate 4 at the rear thereof. The underfeed grate comprises a plurality of downwardly and rearwardly inclined retorts 6 arranged side by side and spaced apart with the outer walls of the outer retorts spaced from the side walls of

the fire box of the furnace. Each of the retorts is provided with a bottom wall 8 and side walls 10. The bottom walls 8 of the several retorts form continuations of the bottom walls, respectively, of fuel hoppers 12, the fuel from the hoppers being fed into the retorts by means of horizontally reciprocating plungers or rams 16. On the upper edge of each of the side walls of the retorts is mounted a row of tuyère blocks 18, the rows of tuyère blocks mounted on the adjacent walls of the retorts being arranged side by side with their inner surfaces in sliding engagement, and the rows of tuyère blocks mounted on the outer walls of the outer retorts extending over the spaces between the outer walls and the side walls of the fire box of the furnace. The overfeed grate 4 is made up of a plurality of sections arranged side by side, each of which is associated with one of the side walls of one of the retorts, and these parts together with the row of tuyère blocks mounted on the side wall are adapted to be moved together as a unit back and forth in a substantially horizontal direction, to assist in feeding the fuel progressively while in the course of combustion rearwardly of the furnace, and to discharge the refuse of the fuel in the usual ash pit located at the rear of the overfeed grate. To enable said units to be thus moved back and forth each overfeed grate section is mounted on a shoe 22 adapted to slide horizontally on a support 24, the lower or rear end of the associated retort side wall being pivotally connected at 26 to the shoe and its upper or forward end being suitably mounted for sliding movement. The means for actuating the several movable units above described comprise links 28 connecting the forward ends of the walls of each retort with the reciprocating feeding plunger or ram 16 associated with the retort.

Except as hereinafter described, the parts above referred to may be and preferably are the same as the corresponding parts of the stoker illustrated and described in said patent to Riley No. 1,322,822 to which reference may be had for a more complete description of the same.

In the embodiment of the present invention illustrated in the drawings each side wall carries a plurality of fuel agitating

- and feeding members 30, the members on the side walls of each retort extending horizontally substantially to the center line of the retort and the members on the two side walls being spaced different distances from the bottom of the retort and being arranged in staggered relation. Each member is wedge-shape in cross section and has one of its faces directed rearwardly of the retort.
- 10 The members may be removably secured to the side walls by means of bolts 32 as shown in Fig. 2 so as to enable them to be easily removed and replaced as desired, or may be cast integral with the side walls, as shown in Fig. 3, in the latter figure one of said members is indicated at 30' and one of the side walls of the retort is indicated at 10'.

With this construction it will be apparent that during the operation of the stoker the members 30 will positively act throughout the length of the retort to cooperate with the tuyère structures carried by the side walls to uniformly feed the fuel down the retorts and distribute it over the tuyère structures. It will also be apparent because of the wedge-shape construction of the members 30 that when the stoker is started after being banked, the members will act immediately to agitate the fuel and thoroughly break up any coke formation within the retort. Under certain conditions it might be desirable to decrease the areas of the fuel pushing faces of the members 30 toward the rear end of the retort, and also the number and relative positions of the members employed can be made to suit the requirements of various fuels.

As will be evident to those skilled in the art, my invention permits of various modifications without departing from the spirit thereof or the scope of the appended claims.

What I claim is:

1. A furnace having, in combination, a downwardly and rearwardly inclined retort 45 having side walls longitudinally movable, means for reciprocating said side walls longitudinally and for feeding fuel into the forward end of the retort, and members carried by said side walls and extending 50 transversely of the retort for acting on the fuel therein, each of said members being of wedge-shape in cross-section and having one of its faces directed rearwardly so as to serve as a fuel pushing face to feed the 55 fuel down the retort during the rearward movement of the side walls.

2. A furnace having, in combination, a downwardly and rearwardly inclined retort having side walls longitudinally movable, 60 means for reciprocating said side walls longitudinally and for feeding fuel into the forward end of the retort, and devices carried by at least one of the side walls for acting on the fuel within the retort substantially 65 throughout the length thereof during said movement of said side walls, said devices being arranged one in front of the other and spaced apart, and each of said devices having a fuel pushing face directed 70 toward the rear of the furnace.

3. A furnace having, in combination, a downwardly and rearwardly inclined retort having side walls longitudinally movable, 75 means for reciprocating said side walls longitudinally and for feeding fuel into the forward end of the retort, and laterally projecting members carried by each of the side walls, spaced a distance apart longitudinally 80 of the side walls, and with the inner ends of the members on the two side walls arranged in close proximity to the same vertical plane, and having rearwardly directed fuel propelling faces for feeding the fuel down the retort.

EDWIN LUNDGREN.
